UNITED STATES PATENT OFFICE.

HENRY E. LONGWELL, OF PITTSBURGH, PENNSYLVANIA, ASSIGNOR, BY MESNE ASSIGNMENTS, TO THE COLONIAL TRUST COMPANY, TRUSTEE, OF PITTSBURGH, PENNSYLVANIA, A CORPORATION OF PENNSYLVANIA.

MEANS FOR OPERATING GAS-PRODUCERS.

1,070,825.

Specification of Letters Patent. Patented Aug. 19, 1913.

Application filed December 23, 1909. Serial No. 534,615.

To all whom it may concern:

Be it known that I, HENRY E. LONGWELL, a citizen of the United States, and a resident of Pittsburgh, in the county of Allegheny and State of Pennsylvania, have made a new and useful Invention in Means for Operating Gas-Producers, of which the following is a specification.

This invention relates to the general class 10 of suction gas producer plants, but more especially to the means of controlling and regulating the amount of gas made, in accordance with the demand on the producer.

Difficulty has heretofore been experienced 15 in the regulation and control of pressure of the gas due to the fluctuations of the load of the source of consumption, and to variations in the condition of the fuel bed in the producer and consequent variations in the 20 resistance it offers to the passage of air and gas through it. If the demand for gas is increased the pressure will decrease. Also if the fuel in the producer should settle down into an unusually compact mass, the 25 pressure will decrease even though the demand for gas should not increase.

It is most desirable that a gas engine should be supplied with gas at a constant 30 pressure, as with variations in the pressure the proportions of gas and air admitted to the cylinder of the engine will vary, since the air is usually supplied at the constant pressure of the atmosphere. Variations in 35 the proportions of gas and air, impair the efficiency of the engine and the regularity of its operation. In some instances the variations become so great as to interrupt the operation altogether.

In cases where the gas is to be used for 40 fuel purposes it is essential that the gas be delivered at a pressure above that of the atmosphere, a condition that does not obtain in the ordinary suction gas producer plant, and it is essential that this pressure shall 45 automatically be maintained constant irrespective of the demand for gas up to the capacity of the plant, as otherwise the proportions of gas and air supplied to the burners may vary to such an extent as to 50 give very inefficient combustion, or even result in a mixture that will not support combustion at all.

In gas producers in which fuels containing a considerable proportion of so called

volatile combustible, or hydrocarbon, are 55 used, the quality of the gas is apt to vary from time to time. For example the gas is liable to be richer than the average for a few moments after charging fresh fuel, or after poking. Consequently it is desirable 60 to equalize these irregularities in quality as well as any irregularities in pressure.

The object of my invention is to effect a suitable and satisfactory control and regulation of the pressure of the gas delivered by 65 a suction gas producer, and to provide means whereby the variations in the quality of gas delivered to the source of consumption will be sensibly reduced. To accomplish this object I propose to place in the 70 gas line from the producer a mixing chamber, to connect the mixing chamber to the inlet of an exhauster, which discharges into the gas line leading to the source of consumption.

The displacement of the exhauster is preferably greater than the maximum normal demand for gas. From the discharge line from the exhauster I carry a by-pass line back to the mixer. In this by-pass line I 80 place a valve controlled by a pressure regulator connected to the gas line leading to the source of supply in such a manner that any tendency to a variation in the pressure will allow more or less gas to be by-passed to the 85 mixer. The constant by-passing of a portion of the gas coming from the exhauster, makes an intimate mixture with the fresh gas entering the mixer from the producer, and in this way tends to average the quality. 90

In the drawings:—Figure 1 is a longitudinal elevation of the producer plant in accordance with my invention. Fig. 2 is a plan of the producer plant.

Referring to the drawings showing one 95 embodiment of my invention, A is a suction gas producer of a standard design with its charging opening at 1, the steam and air opening at 2, and the gas outlet at 3. The gas outlet may consist of a large vertical pipe, whose end may be submerged in a pit, through which the waste water from the scrubber 6 passes, carrying off the heavier impurities of the gas. A branch 5 from the vertical pipe 3 leads to the bottom of the scrubber 6, which may be of any suitable design and construction. The gas passes up through the scrubber 6 into the

horizontal cylinder, or mixer 7. From the header or mixer 7, the gas is drawn through the pipe 8 by means of the exhauster 9, the rotor of which may be driven by an electric motor 10, or by any other suitable means. The exhauster 9 maintains a suction through the mixer 7, the scrubber 6, and back to the producer A, so that the air and steam required by the latter are forced 10 in by the pressure of the atmosphere. At the same time, the exhauster 9 maintains any desired pressure in the pipe line leading to the source of consumption. The exhauster 9 is shown with inlet on the top, the 15 gas entering from the mixer 7, through the vertical pipe 11. The gas is forced through elbows 13 and 14 into the vertical pipe 12, which leads to the source of consumption, as for example a gas engine. Between the 20 vertical pipe 12, and the lower part of mixer 7 is a by-pass pipe or conduit 15, which contains a valve 16, which may be of a butterfly type. The butterfly valve is actuated through a series of levers by a pressure 25 regulator herein shown as a gasometer regulator 17. A pipe 18 connects the gas line with the bottom of the gasometer bell. The gasometer bell may be loaded by means of adjustable weights so that it will rise 30 when the pressure in the gas line tends to exceed any desired limit. If the demand for gas is diminished for reason of a reduction of the load on the engine, or for any other reason, the pressure in the gas line 35 increases causing the bell to rise. This

movement opens the butterfly valve 16 allowing a certain proportion of the gas to be by-passed back into the mixer 7. If on the other hand the demand for gas increases, the gasometer assumes a lower position, 40 thereby closing the butterfly valve to whatever extent is required to maintain the predetermined pressure in the gas line. The continual by-passing of a portion of the gas back into a mixer of considerable volume keeps it well stirred up and insures a greater degree of uniformity in the quality of the gas as delivered to the source of consumption. From the foregoing description it is apparent that my invention automatically controls and regulates the pressure in the system. 50

What I claim is:

In combination, a suction gas producer, a washer, a mixer, an exhauster, means for driving the movable part of said exhauster, a pressure regulator, a by-pass for by-passing the gas back into the mixer, a valve in the by-pass and connecting means between the pressure regulator and the valve whereby movement of the pressure regulator is communicated to the valve. 60

In testimony whereof, I have hereunto subscribed my name this 18th day of December, 1909.

HENRY E. LONGWELL.
